U.S. Cl. D24—1 B

FIG. 1

FIG. 2

FIG. 3

FIG. 4

FIG. 1 is a top plan view of a dental cabinet showing my new design;

FIG. 2 is a front elevation view thereof;

FIG. 3 is a left side elevation view thereof; and

FIG. 4 is a right side elevation view thereof.

No rear view of the dental cabinet is shown or described because it is conventionally plain and unornamented.

I claim:

The ornamental design for a dental cabinet, substantially as shown and described.
